FIG. 3

FIG. 8

UNITED STATES PATENT OFFICE.

GEORGE ZINT, OF WAPAKONETA, OHIO.

GAME APPARATUS.

968,309.

Specification of Letters Patent. Patented Aug. 23, 1910.

Application filed January 17, 1910. Serial No. 538,482.

To all whom it may concern:

Be it known that I, GEORGE ZINT, a citizen of the United States, residing at Wapakoneta, in the county of Auglaize and State 5 of Ohio, have invented certain new and useful Improvements in Game Apparatus; and I do declare the following to be a full, clear, and exact description of the invention, such as will enable others skilled in the art 10 to which it appertains to make and use the same.

This invention relates to improvements in game or amusement apparatus.

One object of the invention is to provide 15 a game apparatus having figures which simulate the catcher and batter of a base ball game and in which the figures are provided with means adapted to be tripped by a blow from a thrown ball, whereby the arms are 20 actuated to represent the motions of catching and batting the ball, means being also provided for turning the batter's head and for restoring the parts to their normal positions after being tripped and operated.

25 Another object is to provide a game apparatus of this character which will be amusing and which at the same time will require more or less skill to set in motion.

With the foregoing and other objects in 30 view, the invention consists of certain novel features of construction, combination and arrangement of parts as will be more fully described and particularly pointed out in the appended claims.

35 In the accompanying drawings, Figure 1 is a diagrammatic perspective view of my game apparatus set up or arranged in position for use; Fig. 2 is a plan view of the operating mechanism showing the legs of the figures in section and illustrating the parts in the positions they assume when set or ready to be tripped; Fig. 3 is a similar view showing the position of the parts after being tripped; Fig. 4 is a front view of the figure 40 representing the catcher; Fig. 5 is a vertical sectional view of the same; Fig. 6 is a similar view taken at right angles to that shown in Fig. 5 or from front to rear of the figure; Fig. 7 is a detail perspective view of one of 45 the catcher's arms; Fig. 8 is a side view of the figure representing the batter; Fig. 9 is a part front and part sectional view of the same figure; Fig. 10 is an enlarged sectional view of the upper portion of the figure shown 50 in Figs. 8 and 9, illustrating the manner of mounting and operating the head; Fig. 11

is a detail horizontal sectional view on the line 11—11 of Fig. 10; Fig. 12 is a similar view on the line 12—12 of Fig. 10; Fig. 13 is a horizontal sectional view through the 60 body taken above the waist line and showing the connection of the bat and the cushioned stop for limiting the movement of the latter; Fig. 14 is a detail longitudinal section of the bat and its connecting device. 65

In the embodiment of the invention, I provide a suitable platform 1 which is preferably surrounded by a guard rail 2 supported on posts 3, as shown in Fig. 1 of the drawing. At the front end of the platform is arranged a suitable stand 4, which is adapted to receive the devices by means of which the movable parts of the figures are operated or restored to their normal position. Secured to the platform 1 at a 70 suitable distance from the front end thereof is a figure 5 representing the catcher of a base ball game. Also arranged on the platform 1 at a suitable relative position with respect to the catcher is a figure 48 representing the batter of the game. The figures representing the catcher and batter are preferably life size and the body portions and legs of said figures are preferably of hollow metal construction. The figure 5 representing 80 the catcher comprises a body portion 5' provided with hollow legs 6 and 7. The lower end of the leg 6 has a slot 8 formed in its outer side and said lower end is rigidly secured to an attaching plate 9. The lower 90 end of the leg 7 is provided with an attaching flange 10. The plate 9 and flange 10 are adapted to be screwed or bolted to the platform 1 whereby the figure is firmly supported in operative position. In the upper 95 portion of the body 5 is formed a socket 11 in which is secured the head 12 of the figure.

In the front side of the figure at about the waist line is formed a circular opening 13 and to the inner edge of said opening is 100 secured a casing 14 which extends back into the body of the figure and the walls of the rear or inner end thereof are inclined rearwardly and downwardly to form an inclined seat for the weight 22 to be described, and 105 said casing has a rearwardly inclined lower wall at the lowest point of which is formed a discharge opening 15, which communicates with a ball discharging tube 16 extending downwardly through the leg 7 and opening 110 at its lower end through the hole 17 formed in the rear side of the leg below the knee.

In the rear portion of the body 5 above the casing 14 is arranged a transverse shaft or supporting rod 18 on which is loosely hung a cushioning plate 19, to the lower portion of which are connected two rearwardly projecting bolts 20 which extend through the rear wall of the body and are provided with retaining nuts as shown. On each of the bolts 20 between the rear side 10 of the body and the adjacent side of the cushioning plate 19 is arranged a coiled spring 21, the purpose of which will herein-after appear. Between the plate 19 and the inclined rear end of the casing 14 is arranged the tripping weight 22, to the upper end of which is connected an operating trip cord or cable 23, which extends upwardly over a guide pulley 24 and thence downwardly around guide pulleys 25 and 26 arranged in the side of the body and in the lower portion of the leg 6 as shown. The lower end of the operating trip cord or cable 23 is connected with the trigger of an operating mechanism herein-after described.

The weight 22 is normally supported in an inoperative position on a suitable supporting lug 27 arranged on the lower walls of the rear end of the casing 14 as shown. The weight when thus supported is in position to be struck by a ball when thrown into the opening 13 and through the casing 14, and when thus struck, will be forced back off from the supporting lug 27 and into engagement with the cushioning weight 19 which absorbs the force of the blow struck by the ball. The weight after having been thus knocked off from the support 27 will drop a suitable distance, thereby drawing upon the trip cord or cable 23 and causing the latter to operate the trigger and thus release the operating mechanism held thereby.

The ball after striking the weight 22 falls back into the casing 14 and rolls out of the same through the opening 15 down the tube 16 and out through the opening 17 in the back of the leg 7. Pivotaly mounted in suitable bearing lugs 28 arranged on the shoulders of the figure are arms 29 which are in the form of curved rods having formed therein at suitable points bearing apertures 29', which are engaged by pivot bolts 30 arranged in the lugs 28, whereby the arms are pivotally connected to the body.

On the inner ends of the rods forming the arms are arranged elongated loops 31 which are engaged by an operating crank 32 secured to the upper end of an operating shaft 33, which is mounted in suitable bearings in the body and leg 6 of the figure. The shaft 33 extends downwardly through the leg 6 and has its lower end journaled in the attaching plate 9. On the shaft 33 is arranged a coiled operating spring 34 one end 60 of which is secured to one of the shaft bear-

ings or other suitable portion of the body of the figure, while the opposite end is secured to a collar 35 arranged on said shaft and secured thereto by a set screw 36. By revolving the collar 35 on the shaft 33 in the proper direction, the spring 34 is coiled or wound to the proper tension after which the set screw 36 is tightened up to secure the collar on the shaft. By means of the spring 34, the shaft 33 is turned in its bearings to cause the crank arm 32 which engages the loops 31 on the end of the arms to swing said looped ends rearwardly, and the outer ends of the arms forwardly, and together, thus simulating the action or movement of the arms in catching a ball. The outer ends of the arms are provided with hands of any suitable construction.

The shaft 33 is provided on its lower end with means for holding the same against operation by the spring 34 until the weight 22 is struck by a ball thrown into the opening 13, whereby the weight is released in the manner described and caused to trip the shaft holding mechanism, thus permitting the spring to actuate said shaft and thereby swing the arms together as in the act of catching the ball. The mechanism for holding the shaft against the tension of the spring comprises a retaining bar 37 which is fixedly secured at its inner end to the lower end of the shaft 33 and projects through the slot 8 in the lower end of the leg 6 and is adapted to work over the plate 9. When the bar 37 is swung back to an operative position, the shaft 33 will be turned against the tension of the spring 34 to cause the crank arm 32 to swing the looped inner ends of the arms forwardly and thereby swing the outer portions of the arms outwardly or to an open position.

The bar 37 is swung back to an operative position by means of a setting lever 38 which is loosely mounted on the shaft 33 above the bar 37 and has connected thereto a coiled retracting spring 39, the opposite end of which is connected to the shaft, whereby after the setting arm has been actuated to set the bar 37, said lever will be swung back to an inoperative and out of the way position. When the bar 37 has been moved to an operative or set position by the lever 38, said bar is secured by means of a trigger 40 which is pivotally mounted on the attaching plate 9 and is swung into position to engage and hold the bar 37 by a trigger operating lever 41 which is also pivotally mounted on the plate 9 below the bar 37 and is provided on one end with an upwardly projecting lug 42, which is engaged by the outer end of the bar 37 when the latter is moved to a set position.

The opposite end of the lever 41 is provided with a right angularly projecting arm having a trigger engaging lug 43 which,

when the lug 42 on the lever is engaged by the end of the bar 37 and said lever thus swung around, will engage the outer end of the trigger and swing the inner end thereof inwardly into the path of movement of the bar 37, whereby after said bar has been released by the setting lever 38, said trigger will catch and hold the arm in a set position thereby holding the shaft 33 against the 5 tension of the spring 34. The outer end of the trigger 40 is connected to the lower end of the trip cord 23 whereby, when the weight 22 is knocked from its support by the ball, said trip cord will be pulled by the 10 weight, and the trigger thus tripped or disengaged from the shaft holding bar 37 thereby releasing said bar and permitting the spring 34 to turn the shaft 33 and thus swing the crank arm 32 back whereby the 15 arms will be brought together in the manner described.

In order that the operator at the front end of the platform may restore the parts to their normal positions, an operating cable 44 20 is provided, said cable being connected at its inner end to the setting lever 38, and after being passed around a suitable guide pulley 45 extends to the front of the platform and around a suitable guide pulley 46 arranged 25 in the stand 4 and thence upwardly through the upper portion of the stand, where the cable is provided with a suitable operating handle 47 which is adapted to be grasped by the operator. When the cable 44 is pulled 30 by the operator, the setting lever 38 will be engaged with the shaft holding bar 37 and said lever and bar swung back to a set position where said bar is caught and held by the trigger 40 as hereinbefore described.

40 When the trigger 40 is swung back by the trigger operating lever 41 as the latter is operated by the setting lever 38 when setting the parts, the movement of the trigger will draw upon the weight operated trip 45 cord 23 thereby raising the weight 22 until the lower edge thereof swings forward into engagement with the weight supporting lug 27, as clearly shown in Fig. 6 of the drawing, wherein it will be seen that the angle 50 of the inner end of the casing 14 holds the weight in an inclined position, causing the lower end of the same to swing forwardly when raised clear of the lug 27.

The figure 48 representing the batter 55 comprises a body portion 48', legs 49 and 50 and a head 51. In the upper portion of the body is formed a socket 52 in which the head 51 is pivotally mounted. In the lower end of the neck portion of the head is 60 formed a central aperture or recess 53 and two sockets 54, one of which is arranged on each side of the recess 53, as shown. The head is held in position by a shaft 55 having a reduced threaded upper end on which is 65 arranged a disk 56. The disk 56 is secured

on the reduced upper end of the shaft by a nut 57 and in the lower side of the disk is formed an annular groove 58. On the upper side of the disk 56 are arranged two pins 59, which are adapted to be engaged with the sockets 54 in the end of the neck portion of the head, thus securing the head to the shaft 55. When the head is thus engaged with the disk, the nut 57 will project up into the recess 53 in the neck. 75

In the bottom of the socket 52 is formed an annular groove 60 and through the center of the bottom of the socket is formed a passage which is adapted to receive the shaft 55 when the head is engaged with the socket. 80 When the head has been engaged with the socket, the groove 58 in the disk 56 will coincide with the groove 60 in the bottom of the socket, thereby forming a ball race which is adapted to receive a series of anti-friction balls, thus providing a ball bearing for the head. 85 On the downwardly projecting lower portion of the shaft 55 is arranged a grooved pulley 61, said pulley being preferably secured to the shaft by a set screw, as shown. 90 On the lower end of the shaft below the pulley 61 is arranged a collar 62, said collar being secured to the shaft by a pin 63, which is inserted therethrough and through an aperture in the shaft, thereby preventing 95 the rotation of the collar on the shaft.

On the collar 62 is arranged a coiled spring 64 the inner end of which is secured to the collar, while the outer end is secured to a fixed part of the body portion of the figure in any suitable manner. The pulley 61 and spring 64 are engaged with the end 100 of the shaft through an aperture 65 formed in the front of the figure at the waist line, as shown. Connected to the pulley 61 is an 105 operating cord 66, said cord being given one or two turns or winds around the pulley, after which the cord passes over a guide pulley 67 arranged in the upper portion of the body of the figure and from said pulley 110 passes down through the leg 50 and around a guide pulley 68 in the lower end of the leg and from thence extends to the front end of the platform 1 and around a pulley 69 in the lower portion of the stand 4 and thence 115 upwardly through the top of the stand where the end of the cord is connected with an operating handle 70 which, when pulled by the operator, will unwind the cable from the pulley, thus revolving the same and the head against the tension of the coiled spring 64. When the handle 70 has been released, the spring 64 will turn the head back and 120 rewind the cord on the pulley. 115

The leg 50 of the figure is provided with a 125 suitable flange or attaching plate 71 which is screwed or otherwise secured to the platform 1, while the leg 49 is provided with an attaching plate 72 on which is arranged a trip mechanism hereinafter described. Ar- 130

ranged in the leg 49 is a bat operating shaft 73, said shaft being revolvably mounted at its upper end in a horizontal plate 74 arranged through the body of the batter at about the waist line, said plate being provided with a centrally disposed bearing aperture to receive the upper end of the shaft, as shown. The lower end of the shaft 73 is revolvably mounted in the attaching plate 72. Arranged on the shaft 73 near its upper end is a coiled spring 75, one end of which is connected to a collar 76 secured to the shaft 73 by a set screw. The opposite end of the spring 75 is secured to the plate 74 or other suitable stationary part of the figure. Before the collar 76 is secured to the shaft, said collar is revolved in the proper direction to wind up the spring 75 until the required tension is imparted thereto.

To the upper end of the shaft 73 above the plate 74 is secured a bat attaching arm 77, with which is engaged a tubular shank 78 secured to the inner end of the bat 79, as clearly shown in the drawings. It will be noted that the shaft 73 is arranged at a slight inclination and that the bat is secured thereto at right angles so that said shaft supports the bat at the angle or inclination at which it is usually held by a batter before striking at a ball.

Pivotedly mounted on a stud bolt 80 secured to the plate 74 is a cushioning plate 81, to the outer end of which is connected a curved guide rod 82, which is adapted to pass through a suitable guide aperture in a stop plate 83, also secured to the plate 74 and between the cushioning plate 81 and the stop plate 83. On the rod 82 is arranged a buffer or cushioning spring 84. The cushioning plate 81 is provided to receive the force of the blow from the bat when swung around by means of the coiled spring on the operating shaft 73, thus preventing the parts from being injured.

Arranged on the shoulders of the figure are pairs of apertured arm attaching lugs 85, between which are pivoted the upper members 86 of rods representing the arms 50 of the batter. The lower members 87 of the rods are connected to the upper members 86 at the elbow by a ball and socket joint 88 whereby the arms have a free movement in any direction. The outer ends or hand portions of the arms are secured to the bat in proper position by means of attaching bands 89, as shown. By thus connecting the arms, they will be moved by the bat when the latter is swung around with the shaft 73 as hereinbefore described.

Rigidly secured to the lower end of the shaft 73 and working through a slot formed in the lower end of the leg 49 immediately above the attaching plate 73 is a shaft holding bar 90, which corresponds to the shaft

holding bar 37 of the catcher. The bar 90 is adapted to be swung around over the plate 72 to turn the shaft 73 and bring the bar to an operative position by means of a setting lever 91, which is loosely mounted on the lower end of the shaft 73 and has connected thereto an operating cord 92 which is passed around a guide pulley 93 which extends forwardly to the front end of the platform and around a pulley 94 arranged in the lower portion of the stand 4 and thence upwardly through the top of the stand where the end of the bar is connected to an operating handle 95 adapted to be grasped by the operator to set the tripping mechanism. After the holding bar 90 has been set by the setting lever 91 and the cord 92 released, said lever is swung back to an out of the way position by a coiled spring 96.

Pivotedly mounted on the attaching plate 72 is a trigger operating lever 97 having right angularly projecting ends one of which is provided with a lever actuating lug 98, which is engaged by the shaft holding bar 90 when the latter is swung to a set position, and on the other end of which is formed a trigger engaging lug 99 which is adapted to be brought into engagement with one end of a trigger 100, the opposite end of which is adapted to be thereby brought into the path of movement of the shaft holding bar 90, so that when said bar is released by the setting lever 91, the trigger will catch and hold the bar in a set position, thereby holding the bat in position for operation until the trigger is sprung and the bar 90 released at which time the spring 75 will operate the shaft 73 and swing the bat around as in the act of striking at the ball.

The trigger 100 is provided with a curved operating arm 101 which is connected by a rod 102 to an operating arm 103 on the end of the trigger 40 of the catcher operating mechanism, whereby when the trigger 40 is sprung or tripped by the cord or cable 23 and the weight 22, the trigger 100 will also be sprung or tripped, thereby releasing the bar operating mechanism.

It will be noted that the operating arm 101 of the trigger 100 has formed in its end an elongated eye or slot 104, with which the end of the rod 102 is connected, said slot being provided to allow for a slight backward movement of the rod 102 when the trigger 40 is set by the trigger operating lever 41, as this and the catcher tripping mechanism are set before the batter mechanism is set.

It will also be noted that when the tripping mechanism of the two figures is set for operation that the trigger of the catcher has a longer engagement with the holding bar 37 than the trigger 100 has with the holding bar 90 of the bat operating shaft 73, so that when the parts are sprung, the bat

operating mechanism is released a little time before the arm operating mechanism of the catcher, the time between the operation of these parts, however, being very slight.

5 The head operating handle 70 may be actuated at any desired time, preferably on the throwing of the ball.

From the foregoing description taken in connection with the accompanying drawings, 19 the construction and operation of the invention will be readily understood without requiring a more extended explanation.

Various changes in the form, proportion 15 and the minor details of construction may be resorted to without departing from the principle or sacrificing any of the advantages of this invention as defined in the appended claims.

Having thus described my invention, what 20 I claim is:—

1. A game apparatus having figures representing players, movable parts arranged on said figures, operating mechanism arranged in said figures to operate said parts, 25 trip mechanism connected with said operating mechanism, means arranged in one of said figures to spring the trip mechanism thereof, said means being adapted to be set in motion by a projectile, and means to operatively connect the trip mechanism of one 30 of said figures with the trip mechanism of the other figure, whereby one is operated by the movement of the other.

2. In a game apparatus, figures representing the catcher and batter of a ball game, 35 movable arms arranged on the figure representing the catcher, a spring actuated arm operating mechanism, a holding device to hold said operating mechanism against 40 the tension of its spring, a weight operated trip mechanism to release said holding mechanism, a bat operating mechanism arranged in the figure representing the batter, a bat connected with said mechanism, a holding 45 device to hold said bat operating mechanism in position for operation, a trip mechanism to release said holding device, means to connect said trip mechanism with the trip mechanism of the catcher, and means to restore 50 the parts to operative positions after being released by said tripping mechanism.

3. In a game apparatus, figures representing the catcher and batter of a ball game, 55 pivotally mounted arms arranged on the figure representing the catcher, a spring actuated arm operating shaft arranged in said figure and connected with the arms to swing the latter together as in catching a ball, a holding bar connected to said arm operating 60 shaft whereby the latter is held in position to operate said arms, a bar operating lever to move said holding bar to a set position, a trigger adapted to be engaged with said bar to hold the latter in set position, a 65 trigger operating lever actuated by the

movement of said bar when swung to a set position, a trigger releasing means adapted to be actuated by a projectile thrown at the figure of the catcher to trip said trigger and thereby release said holding bar and arm 70 operating mechanism whereby the arms of the catcher are swung together as in the act of catching a ball, a bat pivotally connected to the figure of the batter, a bat operating shaft, a holding and tripping mechanism 75 connected with said shaft, means whereby said holding and tripping mechanism is released by the trigger of the catcher releasing mechanism when said trigger is tripped, and means to restore said parts to their normal 80 or operative positions.

4. In a game apparatus, figures representing the catcher and batter of a ball game, 85 said figure representing the catcher having formed therein an opening adapted to receive a projectile thrown at the catcher, a casing arranged around said opening in the body of the figure, said casing having formed therein a projectile discharge opening, a tube connected with said opening and 90 extending downwardly and opening through the rear side of one of the legs of the figure whereby the projectile is permitted to pass out of the body of the figure, arms pivotally connected to the figure, a spring actuated arm operating shaft adapted to swing said arms around as in the act of catching a ball, a holding and tripping mechanism connected with said shaft whereby the same and 95 said arms are held in a position for operation, a weight arranged at the inner end of the casing in the body of the catcher and adapted to be actuated by the projectile, a cord to connect said weight with the tripping mechanism whereby the latter is sprung 100 to release the shaft holding mechanism, means to support said weight in an operative position, a cushion to receive the force of the weight when struck by the projectile, a bat arranged on the figure representing the 110 batter, a spring actuated bat operating shaft, a holding and tripping mechanism connected with said shaft, and means whereby said holding and tripping mechanism is actuated by the holding and tripping mechanism for 115 the catcher.

5. In a game apparatus, figures representing the catcher and batter of a base ball game, arms pivotally mounted on the figure representing the catcher, a spring actuated arm operating device, a weight operated holding and tripping mechanism connected to said arm operating device, a spring actuated bat operating shaft arranged in the figure representing said batter, a bat operatively secured to said shaft, arms connected with said bat and moved thereby, a holding and tripping mechanism secured to said bat operating shaft and means to operatively 120 connect said holding and tripping mechan- 125 130

ism with the holding and tripping mechanism of the catcher, cables connected with said holding and tripping mechanism whereby the latter and the parts connected thereto are restored to positions for operation, a movable head arranged on said batter, and means whereby said head is turned.

6. In a game apparatus, a platform, figures arranged on said platform to represent the catcher and batter of a base ball game, movable arms arranged on the figure representing the catcher, a spring actuated arm operating device whereby said arms are swung together as in the act of catching a ball, a weight operated holding and tripping mechanism connected with said arm operating device whereby the arms are held in position for operation, said weight being adapted to be set in operation by the force of a ball thrown at the catcher, a bat connected with the figure representing the batter, a bat operating device, a holding and tripping mechanism connected with said bat operating device whereby the bat is held in posi-

tion for operation, means to operatively connect the holding and tripping mechanism of the bat operating device with the holding and tripping mechanism of the catcher, cables connected with said holding and tripping mechanism and extending to the front end of said platform whereby said parts are restored to their operative position, a pivotally mounted head arranged on the figure representing the batter, a spring to turn said head in one direction, an operating pulley connected with the head, an operating cable connected to and wound on said pulley whereby the head is turned in the opposite direction, said cable extending to the front end of said platform.

In testimony whereof I have hereunto set my hand in presence of two subscribing witnesses.
